UNITED STATES PATENT OFFICE.

WILLIAM G. NEWTON, OF NEW HAVEN, CONNECTICUT, ASSIGNOR TO THE PECK BROS.
& CO., OF NEW HAVEN, CONNECTICUT, A CORPORATION.

DESIGN FOR A WATER-CLOSET BOWL.

44,180.

Specification for Design.

Patented June 10, 1913.

Application filed March 19, 1913. Serial No. 755,555. Term of patent 7 years.

To all whom it may concern:

Be it known that I, WILLIAM G. NEWTON, a citizen of the United States, residing at New Haven, in the county of New Haven and State of Connecticut, have invented a new, original, and ornamental Design for a Water-Closet Bowl; and I do hereby declare the accompanying drawing to be a full, clear, and exact illustration of the same, and which said drawing constitutes part of this

application, and represents a perspective view of a water-closet bowl embodying my design.

I claim:

The ornamental design for a water closet bowl, as shown.

WILLIAM G. NEWTON.

Witnesses:

C. M. VAN SLYKE,
R. W. HOADLEY.
